BOTTLED BEVERAGE COOLER

Walter F. Vose, Bloomington, Ill., assignor of
sixty per cent to Peter Karonis and B. B.
Karstens, both of Bloomington, Ill.

Application June 20, 1936, Serial No. 86,320

6 Claims. (Cl. 62—7)

An object of my present invention is to provide a cooler for bottled beverages and the like which is highly efficient, yet simple in its construction and inexpensive from a manufacturing standpoint.

A further object is to provide a cooler for articles which are suitable to be cooled by submerging them in cold water, the cooler providing a tank for the water and a cooling means for the water in the tank which forms ice in the form of pencils or the like, and the refrigerating mechanism being so operated that these pencils of ice are formed on the wall of the refrigerator and then freed therefrom so that they can float to the surface of the water, and in so doing induce a circulation in the water which effectively operates to maintain a constant temperature throughout the body of the water.

A further object is to provide a cooler in which articles to be cooled are submerged in cold water and refrigerating mechanism is operable to form ice in small portions or strips, which are periodically freed from the wall of the cooler and serve to prevent the bottles from freezing to the sides of the tank containing the water.

Still a further object is to provide a cooler having a dry compartment in which hanging ice cube trays are arranged on the side walls thereof for keeping a supply of ice cubes for use when desired.

Still another object is to provide a "dual" type of cooler in which a dry compartment and a wet compartment are provided, which are in thermal contact with each other instead of being insulated from each other, thus providing a portion of the cooler having a temperature which is a differential between the temperatures in the dry and wet compartments, and enabling the use of a single evaporating coil for the dry compartment and the wet compartment and a control for the refrigerating mechanism responsive to the portion of the coil extending from one compartment to the other.

A further object is to provide a wet and a dry compartment in a cooler structure so associated with a single temperature responsive device for control thereof which operates to effectively control the refrigerating mechanism for both compartments without any danger of too much hold-over in the wet compartment, and with assurance that the refrigerating mechanism is completely under control for most efficient operation.

Still a further object is to provide a cooler structure in which a tank has corrugations or

other irregular formations on its wall, an evaporator coil of a mechanical refrigerator mechanism being arranged outside the wall and in heat transferring relation thereto by means of ice formed to entirely encase the evaporator coil and contacting with the wall of the tank.

Still a further object is to provide modified forms of ice making units which utilize evaporator coils of refrigerating mechanisms to chill water adjacent the unit and freeze it, preferably in the form of strips or chunks, mechanism being provided for freeing the ice from the ice making units after the ice is formed.

A further object is to provide an ice making unit supplied with refrigerant from a refrigerating mechanism to form ice in pockets or the like of the ice making unit, a control valve being arranged so that, upon the temperature affecting it being reduced to a predetermined degree, the control will operate to permit free flow of the refrigerant by-passing an expansion valve so as to warm up the ice making unit sufficiently to free the ice from contact therewith, so that it can float to the surface of the water in which the unit is submerged to cool the water and induce a circulation thereof.

Another object is to provide a cooler having a tank compartment and a dry compartment, a single evaporator coil being utilized to chill both compartments, the compartments however being thermally isolated from each other.

Still a further object is to provide a cooler cabinet so constructed that the use of expensive dies is eliminated, this construction involving the use of a top rail which can be cut in any length to thus accommodate different sizes of coolers and also vertical rails if desired, in combination with a corner cover member so formed and connected with the cooler frame that it draws the top and vertical rails into intimate contact with the frame and retains them neatly against any possibility of any cracks or other unsightly joints in the exterior surface of the cooler cabinet.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 is a perspective view of a bottled beverage cooler embodying my invention.

Figure 2 is a longitudinal, vertical, sectional view thereof on the line 2—2 of Figure 1, a

portion of the inner tank, back of the water in the cooler, being shown in elevation, and the refrigerating mechanism for the cooler being shown diagrammatically.

5 Figure 3 is a horizontal sectional view on the line 3—3 of Figure 1.

Figure 4 is an enlarged, vertical, sectional view on the line 4—4 of Figure 3, showing how ice is formed in the form of strips and the action of 10 the ice in being released and inducing a circulation in the water.

Figure 5 is an enlarged, sectional view on the line 5—5 of Figure 4, showing how the inner wall of the tank of the cooler may be formed, so as 15 to prevent the formation of a solid sheet of ice on the inner wall of the tank and produce instead strips or "pencils" of ice.

Figure 6 is a diagrammatical view of a modified 20 form of cooling unit for forming chunks of ice 20 in a cooler cabinet.

Figure 7 is a side elevation of the ice forming 25 unit shown in Figure 6 and looking in the direction of the arrow 7 thereon.

Figure 8 is a vertical, sectional view on the 25 line 8—8 of Figure 7.

Figure 9 is a plan view of another modified 30 form of ice forming unit.

Figure 10 is a vertical sectional view of the same on the line 10—10 of Figure 9.

35 Figure 11 is a diagrammatical view showing the refrigerating system for the ice forming units of Figures 6, 7, 8, 9 and 10.

Figure 12 is a sectional view through a control 35 valve used in connection with the system shown in Figure 11.

Figure 13 is an enlarged sectional view through 40 the upper rail of the refrigerator as taken on the line 13—13 of Figure 1.

Figure 14 is a detail, side elevation of an upper 45 corner of the cooler.

Figure 15 is a perspective view of the ends of 50 two of the top rails of the cooler and a corner cover member therefor.

Figure 16 is a similar view showing the parts 55 of Figure 15 assembled together.

Figure 17 is a view similar to Figure 16 showing 60 a modified construction.

Figure 18 is a sectional view on the line 18—18 of Figure 14, showing how the corner cover member 65 cooperates with the top rails during assembly of the cooler; and

Figure 19 is a sectional view on the line 18—18 of Figure 17, showing the corner cover member drawn into place.

55 On the accompanying drawings I have shown in Figures 1, 2, 3, 4 and 5 a cooler having a dry compartment 10 and a bottled beverage compartment 12. The compartment 10 is formed by a bottom wall 14 and side walls 16, the side walls 60 16 being surrounded by a refrigerant coil 18. Outside the refrigerant coil 18 side walls 20 are provided, which are suitably insulated against heat transfer by means of insulation 22. The bottom 14 is likewise insulated by insulating material 24.

The bottled beverage compartment 12 comprises a tank having a bottom 26, end walls 28 and side walls 30. Spaced inwardly from the walls 28 and 30 are corrugated end walls 32 and 70 corrugated side walls 34. The walls 32 and 34 may be termed false walls. The corrugations of these walls, indicated at 36, extend only partially throughout the height of the wall as shown at the left side of Figure 2.

75 A second refrigerant coil 38 is positioned be-

tween the outer end and side walls 28 and 30 and the inner end and side walls 32 and 34. This coil may be an extension of the coil 18, and has a return end connected with a refrigerant compressor 40. The compressor 40 is driven by an electric motor 42 and the usual condenser coil, liquid tank or receiver and expansion valve for the refrigerating mechanism are indicated at 43, 44 and 52 respectively. The motor 42 is preferably automatically controlled, as for instance, by a switch 45 responsive to temperature through the medium of a capillary bulb 46 and a bellows 48 in the usual manner. The capillary bulb 46 is preferably in thermal contact with the portion of the evaporator coil tubing extending from the coil 18 to the coil 38.

In Figures 6 and 7 I show a modified construction which may be termed an "ice forming unit" and in which the evaporator coil is indicated at 50, and the usual expansion valve at 52. The coil 50, as shown in Figure 7, is arranged in a zig zag formation and is covered with a member A provided with pockets 51 to determine the shape of the ice blocks 128 formed in the ice forming unit. The pockets 51 are tapered outwardly to permit ready freeing of the ice as will hereinafter be disclosed. The cover member A is preferably provided with end members 56 which seal off the spaces 58 from the surrounding water 60, so that the spaces 58 constitute air spaces. 30

In Figures 9 and 10 I show another modified construction in which a pair of castings 62 and 64, when associated together as illustrated, form an evaporator unit, the casting 64 having pockets 66 also tapered outwardly in which chunks of ice 35 128 are adapted to form.

A tank 70 is connected with the evaporator unit comprising the castings 62 and 64 and is adapted to contain water 130. I have not illustrated any insulating wall for the cooler shown in Figure 10, 40 but it is, of course, understood that such is provided to gain all the efficiency possible.

For operating the ice forming units shown in Figures 6 and 10 I provide the refrigerating system shown in Figure 11, parts of which are similar to the one shown in Figure 2, and therefore provided with the same reference numerals. The evaporator coil however is indicated at 50. The refrigerant chamber 63 of Figure 10 is the equivalent of the coil 50. 45

A control valve B is illustrated which by-passes the expansion valve 52 and is a normally closed valve which opens due to a predetermined reduction in temperature. For illustrative purposes a bellows 76 is connected with a capillary bulb 78 at the return end of the coil 50 (see Fig. 11). The operation of this valve will hereinafter appear under the heading of practical operation. 55

In connection with the construction of my cooler system certain problems were encountered, especially in connection with making the outer shell in an economical manner without the expense of building large expensive dies for forming the outer shell. As shown in Figure 13 there is an outer sheet metal cover 80 surrounding the insulation 22, this cover being put on in the form of flat sheets, as illustrated in Figure 3, having rounded corner strips 82 and top rails 84. The cross sectional details are all shown in Figures 13, 18 and 19 but omitted from Figures 2 and 3 where the scale of the drawing is too small to permit such details to show clearly. 60

Neatly joining the ends of the top rails 84 and the vertical rails 82 cannot be economically done with welding, brazing or the like, and I have pro- 70 75

vided a corner cover member C which covers the joints and yet holds the rails 82 and 84 all firmly in contact with the frame of the cooler with the use of but a single screw 86.

- 5 The corner cover member C has a downwardly extending flange 88 and a pair of laterally extending flanges 90. These, as shown in Figures 18 and 19 are initially formed to extend at a slight angle inwardly so that their edges contact with the rails 82 and 84, and when the screw 86 is tightened, as in Figure 13, they effectively bind against the rails to permanently retain them in position without possibility of any open spaces between the edges of the cover C and the rails 82 and 84.
- 15 With this construction it is possible to form the rails in any length on one pair of dies or rollers, and the cover member C on another pair of dies, which need not be large, yet by cutting the rails to the desired lengths, the construction is adaptable to all sizes of cooler cabinet constructions.

20 A further feature enhancing the appearance of the construction is in the use of flanges 82 on the top rails 84, and small flanges 94 on the corner cover member C which hook over the flanges 92 to position the parts 84 and C relative to each other. If desired, the rail 82 and the corner cover member C can be combined in a single piece 83 shown in Figure 17.

25 The frame of the cooler includes a water tank sill 96 (see Figure 13) and a top rail sill 98. The sill 98 is suitably stepped for the edges of the sliding lids 100, 102 and 104, which lids are preferably formed of insulating material. Metal liners 106 are provided for the edges of the lids 30 to slide on, and these have flanges 108 at their outer edges. These flanges, as well as the flanges 92 of the top rails 84, are located in grooves 110 of the sill 98. Interposed between the flanges 92 and 108 are strips 112 of rubber or the like serving 35 the purpose of insulating breaker strips to prevent transmission of heat from the top rails 84 through the sheet metal liners 106 to the interior of the cooler.

Practical operation

40 In the operation of the cooler shown in Figures 1 to 5, the switch 45 is so set that the refrigerant compressor 48 will continue to operate until pencils of ice 114 are formed, as in Figures 4 and 5. At first small bumps of ice, indicated by dotted lines at 116, are formed and these gradually thicken until the pencils 114 are the result. Before the pencils 114 form, however, the water surrounding the evaporator coil 38 will freeze, first 45 as indicated at 117 and then as indicated at 118, which serves as a solid medium between the coil 38 and the corrugated portions 36 of the walls 32 and 34 to increase the efficiency to the maximum. The water in the space surrounding the coil 38 will be at substantially the same level as the water within the cooler and indicated at 120, since the walls 32 and 34 are not sealed along their lower edges to the bottom wall 26 but merely rest thereon.

50 After the pencils of ice are formed, as indicated at 114, the switch 45, due to its setting, de-energizes the motor 42, whereupon heat transferred from the water 120 to the walls 32 and 34 melts the pencils 114 loose so that they rise as indicated 55 by dotted lines 114a in Figure 4, and finally rest in a position floating on the surface of the water as indicated at 114b. This operation may take anywhere from 10 to 15 minutes. As these pencils melt, they break up into individual pieces indicated at 114c, which can freely circulate among

the bottles of beverage 122 shown in Figure 2. The bottles are preferably placed in crates 124 which are sufficiently large to hold a dozen bottles and are provided with handles 126 for lifting them out of the water 120.

5 The bottles of beverage 122 shown in Figure 2. The bottles are preferably placed in crates 124 which are sufficiently large to hold a dozen bottles and are provided with handles 126 for lifting them out of the water 120.

10 In loosening from the walls and rising to the surface of the water 120, the pencils of ice 114 induce a circulation in the water (see arrows a in Figure 4) which tends to keep the entire body of water at substantially the same temperature 10 without the necessity of providing any other means for this purpose.

15 By making the walls 32 and 34 of corrugated shape, the pencils 114 are isolated from each other by the peaks of the corrugations, although it is obvious that other shapes and different shapes of corrugations than those illustrated can be used for accomplishing the same purpose.

20 With the use of the coils 18 and 38, which are actually a single coil arranged as illustrated, I am able to effectively cool the compartment 10 and form ice in the compartment 12. The coil 18 being the colder coil provides the necessary drop in temperature to efficiently cool the compartment 10, while the relatively warmer portion 25 of the evaporator coil indicated as 38 is still sufficiently cold to form ice as desired.

25 The ice forming units A and 62—84 of Figures 6 and 10 respectively form ice in the pockets between the corrugations of the member A in Figure 6 and in the pockets 66 of Figure 10, as indicated at 128. After the chunks of ice 128 are formed, it is obvious that a warmer liquid flowing through the coil 50 and the space 68 respectively will soon melt the chunks of ice loose so 35 that they rise, as indicated at 128a, and finally float on the surface of the water 130, as indicated at 128b.

30 It is also obvious that freeing of the chunks or cakes of ice can be accomplished quickly with very little rise in temperature of the coil 50 and the space 68. This is accomplished by the control valve B in Figures 11 and 12, which, upon the coil 50 becoming excessively low in temperature adjacent the bulb 78 due to the ice 128 having formed, is opened so that the refrigerant is pumped directly from the receiver 44 through the coil 50 without expanding through the valve 52. The refrigerant will therefore be relatively 40 warmer, and in flowing through the coil 50 will 50 warm it so that the cakes of ice 128 are loosened and will accordingly float to the surface of the water. This operation may take anywhere from 5 to 10 minutes.

45 As soon as the warm refrigerant affects the bulb 78, however, the valve B will be closed, so that thereafter normal refrigeration takes place with the refrigerant passing through the expansion valve 52.

55 The motor 42 in Figure 11 can be controlled by a control switch such as the one indicated at 45 in Figure 2 to prevent excessive operation of the refrigerating mechanism when not needed, the valve B operating independently to free the cakes of ice 128 whenever they have formed 60 in sufficient size to be practical for use.

65 As the cakes 128 float up through the water, they, of course, induce a circulation which, as heretofore explained, is desirable. The pockets 64, of course, may be of any shape desired. I 70 have shown them as being square, but it is obvious that they can be round, star shape, or any shape which might suit the fancy of the designer.

75 In connection with the dry compartment 10

as shown in Figures 2 and 3, if it is desirable to form ice cubes, an ice tray 130 can be hung along one or more sides of the compartment in a vertical position, flatwise against the wall thereof. These trays, as illustrated in cross section in Figure 2, are relatively flat horizontally and tapered so that after they are formed full of ice, the ice can be readily removed by running enough water over the tray to loosen the ice.

10 For supporting the trays 130 any suitable means may be provided, such for instance as hooks 132 adapted to hook in slots 134 of the side wall. This arrangement provides a convenient means for making slabs of ice without appropriating a prohibitive amount of the space within the compartment 10. After the slabs of ice are removed from the trays 130, they can be broken into cubes with an ice pick or the like.

15 Some changes may be made in the construction and arrangement of the parts of my device without departing from the real spirit and purpose of my invention, and it is my intention to cover by my claims any modified forms of structure or use of mechanical equivalents which may 20 be reasonably included within their scope.

I claim as my invention:

1. In a bottled beverage cooler, a container, water therein, an inner wall within said container, refrigerating mechanism having an evaporator coil surrounding said inner wall and means for controlling said refrigerating mechanism to cyclically form ice on said inner wall and then melt such ice free of the inner wall whereupon it floats to the surface of said water.
2. In a bottled beverage cooler, a container, a false wall therein and spaced therefrom, said false wall having pocket-like depressions, water in said container on both sides of said false wall, refrigerating mechanism having an evaporator coil in contact with said pockets, ice bridging the space between said evaporator coil and pockets and means for controlling said refrigerating mechanism to cyclically form ice on the opposite side of said false wall and in said pockets and then melt such ice free of such pockets whereupon it floats on the surface of the water.
3. In a cooler, a dry compartment, a wet compartment, a portion of one compartment being in thermal contact with a portion of the other compartment, water in said wet compartment, refrigerating mechanism including an evaporator coil

having a first portion for cooling said dry compartment and a second portion for cooling said wet compartment and a controller for said refrigerating mechanism having a temperature responsive element responsive to the temperature 5 of the evaporator coil between said portions thereof.

4. In a cooler of the character disclosed, a tank, water therein and an ice forming unit submerged in the water, said ice forming unit comprising a 10 member having pockets tapered outwardly, an evaporator passageway within said unit for refrigerant, refrigerating mechanism for pumping refrigerant through said passageway, said refrigerating mechanism including an expansion 15 valve and a control mechanism comprising a temperature responsive valve responsive to a relatively low temperature of said ice forming unit to open and permit refrigerant to by-pass said expansion valve and to a relatively high temperature of said ice forming unit to close and thereby 20 permit the refrigerant to flow only through the expansion valve.

5. In a bottled beverage cooler, a container, water therein, a false wall within the container 25 in contact with the water and spaced from the wall of the container, refrigerating mechanism having an evaporator coil between said false wall and the wall of the container and means for controlling said refrigerating mechanism to 30 cyclically form ice on said false wall at spaced points only and then melt such ice free thereof whereupon it floats in the water and induces a circulation in the water.

6. In a cooler of the character disclosed, an ice forming unit comprising a member having a wall against which ice may be formed, an evaporator passageway in thermal contact with said wall, refrigerating mechanism for pumping refrigerant through said passageway, said refrigerating mechanism including an expansion valve 40 and a control mechanism comprising a temperature responsive valve responsive to a relatively low temperature of said ice forming unit to open and permit refrigerant to by-pass said expansion valve and to a relatively high temperature of said ice forming unit to close and thereby 45 permit the refrigerant to flow only through the expansion valve.

WALTER F. VOSE. 50
